(57) **CLAIM**

The ornamental design for a speaker microphone assembly for a communication device, as shown and described.

DESCRIPTION

FIG. 1 is a front elevational view of a speaker microphone assembly showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top, front, and left side isometric view thereof.

The broken lines shown herein are for illustrative purposes and form no part of the claimed design.
